DEVICE IN CAPPING MACHINES

Josef Einar Jonsson, Linkoping, Sweden

Application June 2, 1937, Serial No. 145,925
In Austria June 6, 1936

5 Claims. (Cl. 226—85)

The present invention relates to machines for capping containers, such as bottles of various kinds, which machines are provided with one or more capping heads movable up and down relatively to the container and within certain limits. One object of the invention is to simplify the construction of the capping head, and another object is to provide a fine adjustment of the head according to the bottle heights, said adjustment taking place completely automatically. By this fine adjustment the advantages of the simplified construction of the head may be utilized in such a manner that the machine becomes rather insensible to bottle height variations and will satisfy very high demands on quick and effective capping. By the invention the machine will be independent of springs previously used for providing for a self-adjustment according to the bottle height variations.

20 Constructional forms of this invention are illustrated in the accompanying drawings.

Figure 1 is a diagrammatical side view of the machine in its simplest embodiment.

Fig. 2 shows, on a larger scale a vertical section 25 of the capping head.

Fig. 3 shows the upper portion of the capping head in a vertical section similar to that of Fig. 2 but with the working parts in different working positions.

30 Fig. 3a shows a vertical section of the lower portion of the working head at an angle of 90° to the corresponding portion in Fig. 2 and with the working parts in different working positions.

Figure 4 shows another embodiment of the machine in side view, and

Figures 5, 6 show part of this machine on a larger scale with the working parts in different positions, Figures 5 and 6 being vertical sections perpendicularly to the view in Figure 4.

40 Figure 7 is a side view of the upper part of a third embodiment of the machine, and

Figures 8, 9 and 10 on a larger scale show details of the last mentioned embodiment.

Figure 8 is a vertical section on the line VIII—

45 VIII of Figure 7, and

Figure 9 is a section, viewed from above, on the line IX—IX of Figure 8.

Figure 10 is a section, viewed from above, on the line X—X of Figure 7, and

Figures 11, 12 and 13 show the same sections, the parts being in other positions; this Figure 13 corresponds to the line XIII—XIII of Figure 7.

The frame of the machine comprises a hollow base 1 and a hollow column 2. The capping head 3 is mounted in a casing 13 provided at the upper

end of a bar 4, which is adapted to be raised and lowered in the column 2. The part 6 of the casing 13 rests on a shoulder of the bar 4 the narrower end of which is provided with threads on to which securing nuts 5 are screwed. The column 2 carries an arm 7 for the container support 8 which is adapted to be fixed at different heights by means of a control and fixing screw 9. The bar 4 with the casing 13 is held in its upper position by means of a spring 11 attached to the base 1 and is lowered into working position by means of a foot lever 10 pivoted in the base 1, at 11, and connected with the bar 4, at 12.

The capping head 3 has cylindrical shape and extends into the casing 13, in which it is displaceable in guides 14, 15. Into the covering plate 15a of the head 3, which plate is located in the guide 15 (Figure 2), there is screwed a bolt 16, which is guided vertically in an adjustable nut 16a screwed into the casing 13. In inoperative position the head 3, by means of the bolt 16, hangs by the casing 13 by means of the stop nut 17, which is screwed on to the free end of the bolt 16 and which rests against the guiding nut 16a before operation. The upper termination of the casing constitutes an unscrewable protecting capsule 16b. In the lower portion of the capping head there is provided, as usual, a pressing member or plunger 18, which is movable up and down. Between its lower end and an unscrewable ring 19 the usual elastic ring 19a is arranged, which is pressed around the cap. In a bore of the plunger 18 there is provided a pressing member or plunger 20, which exerts the required tightening pressure of the cap against the mouth of the container in the working position. In the plunger 18 there is a radial slot 21 for a bolt 22, which is mounted in the head 3 and to which the plunger 20 is attached. The plunger 18 is displaceable independently of the head 3 and correspondingly to the play between the bolt 22 and the slot 21.

Against the upper end of the plunger 18 there rest the lever arms 23, one for each joint lever. The upper arms 24 of the joint levers are pivoted on pins 25 secured in the upper part of the head 3. The upper and lower arms 23 and 24 of each joint lever are united by the joints 26. In the casing of the capping head at places opposite to each other there are mounted two stops 27, which are formed as rollers and which cooperate with the upper arms 24 of the joint levers and extend into their paths, respectively. When the head 3 hangs by the nut 16a (Figure 2) there is a certain play between the rollers 27 and the arms 24 of the joint levers.

The device operates as follows. When a bottle 29 placed on the support 8 is to be capped the casing 13 and also the head 3 are moved downwards by lowering the bar 4 by means of the foot 5 lever 10 during which operation the plunger 20 strikes against the bottle head and stops. The casing 13, however, continues downwards, during which movement the spring 30, which rests against the head 3 and against the nut 16a, contracts and the pressure of the plunger 20 against the top of the cap cover increases in a corresponding degree. Finally, the rollers 27 come into contact with the arms 24 and press the latter inwards (against each other) by which the 10 plunger 18 is pressed downwards the ring 19a is compressed and the bottle cap is deformed and fixed. Upon release of the foot lever the moved parts of the machine and of the capping head return to their initial positions under the action of the springs 30, 31.

By means of the described capping head construction it is possible to vary the capping pressure at will and in spite of this to keep the tightening pressure of the cap against the mouth of 25 the bottle relatively small, so that there is no risk of crushing the neck of the bottle. Instead of moving the casing the support 8 may be moved up and down during the capping operation. Thus, the casing 13 is stationary. Likewise, the 30 capping heads, both in bottle capping machines for manual operation and in automatically working machines with a plurality of heads, may be replaced by the head according to this invention.

The capping head hereinbefore described and 35 others of the same type, in which the tightening and fixing pressure is effected by the movement of the head relatively to the container to be capped, should be equipped with a device for preliminary or coarse adjustment as well as for fine 40 adjustment of the container and the head in vertical direction in relation to each other.

According to this invention the fine adjustment takes place automatically and the principle of 45 this fine adjustment or control in respect of the bottle heights is based upon the fact that the bar 4 is movable relatively to the casing 13 but may be coupled with the latter, so that the length of stroke of the casing, when the bar is moved downwards, is controlled automatically according 50 to the bottle height, the length of stroke of the bar, however, being constant. Hereby the foot lever 10 may always be pressed down just as much independently of the bottle height, or, if the bar or the corresponding member is mechanically driven, resilient members of the driving 55 mechanism, which otherwise have to compensate for variations of the bottle height, become superfluous. The accompanying drawings illustrate two embodiments of this device.

In both of the embodiments the sleeve or 60 shoulder 6 on the casing 13, which sleeve or shoulder surrounds the bar, is movable along the bar, and in openings 34 in the walls of the sleeve there are mounted catches 35, each of which is able to engage its row of teeth 36 on the bar. When the engagement takes place the casing 13 is locked to the bar and has to move with the same as long as the engagement continues.

According to Figures 4-7 there are, on the bar 65 70 75 77 79 80 81 82 83 84 85 86 87 88 89 90 91 92 93 94 95 96 97 98 99 100 101 102 103 104 105 106 107 108 109 110 111 112 113 114 115 116 117 118 by means of a spring 54, acting on the arms 46 as is shown in Figure 9.

The preliminary or coarse adjustment of the head 3 in this embodiment is effected by moving 5 the ring 38 along the bar 4.

In Figure 7 the bar 4 is presupposed to receive its motion by mechanical power.

Having now described my invention, what I claim as new and desire to secure by Letters Patent is:

1. In a capping head for applying caps to bottles, the combination of a casing, a supporting member movable in said casing and carrying a movable pressure block, means controlled by said 15 pressure block to engage and deform the skirt of the bottle cap about the mouth of a bottle to seal the same, a pair of pivoted joint levers, each comprising an upper and a lower link, said joint levers being carried by the supporting member 20 and adapted to transmit pressure to said pressure block, and stops arranged in the casing and in the paths of movement of the upper links of said pair, whereby relative movement between said supporting member and joint levers and 25 said stops will cause the latter to engage the said upper links and cause the pressure block to move in the capping direction to seal a cap.

2. A capping head for applying caps to bottles as claimed in claim 1, including two or more pairs of pivoted links and corresponding shoulders in the capping head symmetrically of the axis of pressure. 5

3. A capping head for applying caps to bottles, as claimed in claim 1, in which said stops comprise rollers, whereby a minimum of friction is set up upon contact of the links and rollers.

4. A capping head for applying caps to bottles, 10 as claimed in claim 1, in which each pair of links comprises an upper link pivotally mounted in said supporting member and pivotally connected to the upper end of the lower link, each of said upper links being provided with an extension projecting beyond the pivotal point of the two links to provide a track for the stop in the depressed position of the head. 15

5. A capping head, as claimed in claim 1, in which the upper end of the casing carries a union 20 having a guide passage to receive the upper end of the supporting member, and a cap carried by the union to provide an extension for the casing and to enclose the upper end of the supporting member. 25

JOSEF FINAR JONSSON.
